Primary Examiner — Cynthia Ramirez*(74) Attorney, Agent, or Firm* — Manuel de la Cerra(57) **CLAIM**

The ornamental design for a cart, as shown and described.

DESCRIPTION

FIG. 1 is a top perspective view of a cart.

FIG. 2 is bottom perspective view thereof.

FIG. 3 is a top perspective view thereof, with the addition of decking.

FIG. 4 is a top view thereof.

FIG. 5 is a bottom view thereof.

FIG. 6 is a left side view thereof.

FIG. 7 is a right side view thereof.

FIG. 8 is a front view thereof; and,

FIG. 9 is a rear view thereof.

The broken line showing of parts of the drawings is included for the purpose of illustrating use and environment, and forms no part of the claimed design.

1 Claim, 7 Drawing Sheets(56)
